UNITED STATES PATENT OFFICE

2,161,671

DOOR CATCH

Hiram Benjamin Gallinger, Superior, Wis.

Application June 14, 1937, Serial No. 148,138

10 Claims. (Cl. 292—78)

This invention relates to improvements in door catches and lifters therefor, the principal object of the invention being to produce a more practical and efficient device of this character than heretofore known, and one in which the operable members are as completely housed as possible.

Another object is to produce such a device which is more positive in action and one that will care for a door in extreme disaligned position with the door frame.

Other objects and advantages of the invention will appear in the following description thereof.

Referring now to the accompanying drawing, forming part of this application, and wherein like reference characters indicate like parts;

Figure 1 is a central vertical section of one embodiment of the device in open position and in the act of catching a closing door.

Figure 2 is a front elevation of the device after such reception and holding the door in closed position.

Figure 3 is a perspective view of the device in the position shown in Figure 1 of the drawing.

1 represents a door such as a screen or storm door or the like, and 2 the door trim, upon which the catch is installed as by the screws indicated at 3 through the base plate 4 thereof. This base plate 4 is of substantially U-shape in cross section having the outwardly extending somewhat triangularly shaped side walls 5 at the lower extremities of which as at 6 is the through pin, supporting externally of said side walls 5 the box like housing 7 which oscillates back and forth on said pin as the door is opened or closed. The upper edges of the side walls 5 are provided with notches 8 in which is pivotally supported the trigger member 9 which is bifurcated at its innermost extremity forming finger like side members 10 which have inwardly projecting therefrom the lugs 11 which rest within the notches 8 and permit ready rockable motion of the trigger. The free end of this trigger extends through a suitable opening 20 in the top of the housing 7 for cooperative engagement with the finger projection 14 thereof when engaging the door carrying member or roller. Intermediate of the fingers 10 of the trigger and in the body portion thereof is formed a hole 12 for hooked engagement with the upper end of the contractile helical spring 13, the opposite end of this spring being hooked about the pin 6 which pivotally supports the housing 7, previously described. The upper end of the housing 7, and upon its innermost edge, is provided with a finger like

projection 14 which cooperates with the trigger 9 in gripping or releasing the roller 15 carried upon a finger like projection 16 secured to the face of the door 1 and adjacent the edge thereof. It will be noted by this construction that when the housing 7 is in its outermost extreme position the axial alignment of the spring 13 is slightly at an angle to the line of draft which would hold the housing in an unbiased condition, so that in this position it is normally biased towards its open position ready for the reception of the cooperative attachment carried by the door, whereas when impinged by such attachment with the door with any degree of force as when the door is swung shut it will carry the 15 housing slightly towards the door opening together with the otherwise free end of the spring beyond that inactive line of stress and bias the housing towards closed position, thus carrying the door to like position for engaging same.

In Figures 1 and 3 the relation of the cooperative parts of the catch may indicate that the door is slightly more correctly hung and free from sag that is usually the case. However, even in such illustration, it is apparent that the door attachment when engaging the finger 14 is slightly lower than when carried to a fully closed position as illustrated in dotted lines, Figure 1, and full lines Figures 2 and 3, where it is slightly raised by the lifting action of the housing 7, 30 governed by its pivotal support 6. Were the door considerably more sagged, a like or greater lifting action would occur when the door closed and thus insure its freedom over the threshold of the door and its satisfactory closing.

As a device for lessening the noise incident to the closing or slamming of the door there is illustrated a rubber cushion or pad 17 held in position by one of the screws 3, or otherwise as desired so that the arcuate base portion of the finger 14 may engage same as the door is closed and thus cushion the sound of same.

Having thus described my invention, what I claim and desire to secure by Letters Patent, is:

1. In a door catch and lifter a vertically elongated U-shaped member, fixed adjacent the edge of a door opening, a box-like housing externally of said member and pivotally supported upon the lower extremities of the side walls of said member, a finger projecting upwardly from the inner open upper face of said housing, a trigger member rockably engaged upon the side walls of said U-shaped member and extending through an opening in the upper end of said housing for cooperative action with said finger, a contractile 50

spring fixed at one end to said pivotal attachment of said housing and at the other end to said trigger whereby said housing is biased in either of its extreme positions, and a second finger member attached to said door in such a manner as to engage said first finger when the door approaches its closed position whereby said second finger is caught between said first finger and trigger and the door both raised and held securely closed.

2. A door catch comprising a channel shaped bracket portion, a housing pivoted adjacent one end to said bracket portion and having an opening through one end, a trigger pivotally held at one end intermediate the other end of said housing and bracket and having a finger projecting through said opening, and means for biasing the trigger and housing toward the limit of movement in either direction.

3. A door catch comprising a channel shaped bracket portion, a housing pivoted adjacent one end to said bracket portion and having an opening through one end, a trigger pivotally held intermediate the other end of said housing and bracket portion and projecting through said opening, and a spring for biasing the trigger and housing toward the limit of movement in one direction upon contact of said projection with a fixed object.

4. In a door catch and lifter for cooperative engagement with a fixed projecting member, a bracket member, a swingable housing pivotally mounted upon said bracket member, a trigger one end of which is pivotally mounted on said bracket and the other end of which extends through said housing, and means within said housing for biasing it toward the limit of its movement in either direction and holding said trigger pivotally engaged to said bracket.

5. In a door catch and lifter for cooperative engagement with a fixed projecting member, a bracket member, a swingable housing pivotally mounted upon said bracket, a trigger one end of which is pivotally mounted on said bracket and the other end of which extends through said housing, and a spring within said housing connected at one end to said trigger and at the other end to said bracket member for biasing said housing toward the limit of its movement in either direction and holding said trigger pivotally engaged to said bracket.

6. A combined door catch and lifter of the

type described including a rockable housing portion, a contractile spring for biasing the housing toward the limit of its movement in either direction, a pivotal trigger cooperatively connecting the spring to the housing portion, said housing and trigger being adapted to extend in the path of and cooperatively engage a fixed cooperative member positioned in a plane slightly below the free end of the housing whereby to lift said fixed member upon the free end of the housing and hold same by the stress of the spring applied indirectly through the trigger.

7. In a door catch, a bracket portion having spaced side walls with notches in an edge thereof, a housing pivotally mounted adjacent one end to the sides of said bracket portion and having an opening through its other end, a trigger having a finger extending from one end thereof and projecting through said opening, and lateral lugs at the other end for pivotal support in said notches, spring means connecting said trigger and bracket and holding the lugs in said notches and biasing the trigger and housing toward the limit of movement in one direction.

8. In a door catch having a bracket portion and a trigger portion pivotally associated therewith, a pivotal connection therefor comprising a notch in an edge of said bracket and a lug on said trigger extendable in said notch, and a spring connecting said trigger and said bracket and holding said lug in said notch.

9. In a door catch having a bracket portion and a trigger portion pivotally associated therewith, a pivotal connection therefor comprising a notch in an edge of one of said portions and a lug on the other of said portions extendable in said notch, and a spring connecting said portions and holding said lug in said notch.

10. In a door catch and lifter for intermittent cooperative engagement with a fixed projecting member, a bracket member, a housing pivotally mounted on said bracket member, one end of said housing when at the limit of its movement in one direction being below the plane of the axis of said projecting member and above same when at the limit of its movement in the other direction, and a spring for biasing said housing toward the limit of its movement in either direction, whereby said housing is adapted for lifting and holding engagement with said fixed projecting member.

HIRAM BENJAMIN GALLINGER.
